UNITED STATES PATENT OFFICE.

JOHN L. KELLOGG, OF BATTLE CREEK, MICHIGAN.

DESIGN FOR A BISCUIT.

48,001.

Specification for Design.

Patented Oct. 19, 1915.

Application filed October 14, 1914. Serial No. 866,710. Term of patent 14 years.

To all whom it may concern:

Be it known that I, JOHN LEONARD KELLOGG, a citizen of the United States, residing at Battle Creek, in the county of Calhoun and State of Michigan, have invented a new, original, and ornamental Design for a Biscuit, of which the following is a specification, reference being had to the accompanying drawing, forming part thereof.

The figure is a perspective view of a biscuit, showing my new design and the vari-

able waved ribbon-like form of the individual shreds of which the design is composed.

I claim:

The ornamental design for a biscuit, as shown.

JOHN L. KELLOGG.
